UNITED STATES PATENT OFFICE.

LOUIS A. HARTMANN, OF BROOKLYN, NEW YORK.

MEANS FOR PROPELLING BOATS.

No. 874,890.

Specification of Letters Patent.

Patented Dec. 24, 1907.

Application filed August 10, 1906. Serial No. 330,006.

To all whom it may concern:

Be it known that I, LOUIS A. HARTMANN, a citizen of the United States, and resident of Brooklyn, in the county of Kings and State 5 of New York, have invented certain new and useful Improvements in Means for Propelling Boats, of which the following is a specification.

My invention relates to improvements in 10 means for propelling boats.

On account of the lack of opportunity or adaptability many persons are unable to properly row a boat, with the result, in some instances, that much energy is wasted, and in 15 others that the boat is caused to capsize, thus rendering this form of enjoyment undesirable and dangerous.

My invention therefore has for its object to provide simple, inexpensive and effective 20 means for manually operating a screw propeller and for controlling the rotations thereof, whereby small boats, such for instance as row boats, can be as easily propelled, the speed controlled and the same rate of speed 25 attained, by an equal degree of energy exerted, by a novice as by an expert.

In the drawings: Figure 1 is a longitudinal sectional view of a boat installed with my propelling means. Fig. 2 a transverse vertical sectional view thereof.

In both figures of the drawings illustrating my invention like reference characters designate corresponding parts.

Referring to the drawings, 1 designates a 35 small boat, preferably of the size and style known as a row boat and having a rudder 2.

Within the boat, at approximately a central point between its bow and stern, is secured a base 3 upon which is mounted a casing 4 in which are rotatably journaled short shafts 5, 6, 7, 8 and 9 having a graduated 40 train of gears secured thereon, the lower gear of which is a worm gear. The ends of the shafts 5 and 6 project beyond the casing and are squared to adapt them to receive and be turned by a crank, whereby if the shaft 5 be turned, what I term as, high speed will be attained and if the shaft 6 be turned, what I term as, low speed will be attained. One

50 end of the shaft 8 has a fly wheel 10 secured thereon and a brake lever 11 is pivoted on the casing and adapted to be forced into engagement with said wheel, against the action of a spring 12, to slow down or stop the train of 55 gears and thereby slow down the speed of the

boat or stop it entirely. On the inner end of the shaft 13 of the propeller 14 is secured a worm 15 which meshes with the lower gear of the gear train, thereby transmitting power therefrom to the propeller shaft. By this arrangement it will be seen that a person can sit 60 or stand facing the bow of the boat while operating the driving and braking mechanisms.

The operation of controlling and propelling the boat is as follows: If high speed is desired the crank is placed on the squared ends of the shaft 5 and turned thus starting the train of gears and through the medium of the connection of the lower worm gear with the worm on the propeller shaft the propeller is 65 driven and if it is desired to slow down or stop the boat the foot is pressed down on the brake lever forcing its shoe into engagement with the fly wheel. If low speed is desired the crank is removed from the end of the upper shaft and placed on one end of the shaft 6, thus cutting out the upper gear 5 of the 70 train and reducing the speed.

I do not wish to be understood as limiting myself to the precise details and arrangements of parts shown and described, but reserve the right to all modifications within the scope of my invention.

Having now described my invention what I claim as new and desire to secure by Letters 85 Patent, is:—

1. In a boat, a propelling shaft provided on one end with a screw-propeller and on the other end with a worm gear, a base, a frame mounted on said base, short shafts journaled in said frame, and the ends of a plurality of said shafts projecting through said frame and being squared to receive a crank, a train of graduated speed changing gears secured on said shafts, the lower gear of said train meshing with the gear on the propeller shaft, a fly wheel secured on one of said shafts and a foot operated brake-lever adapted to be forced upwardly to engage said fly-wheel to stop the movement of said gears and be automatically drawn downwardly out of engagement with the fly-wheel, substantially as described.

2. In a boat, a propelling shaft provided on one end with a screw propeller and on the other end with a worm gear, a base, a frame mounted on said base, short shafts journaled in said frame and the ends of the plurality of said shafts projecting through said frame and being squared to receive a crank, a train 110

of graduated speed changing gears secured on said shafts the lower gear of said train meshing with the gear on the propeller shaft, a fly wheel secured on one of said shafts and 5 a foot operated pivoted brake lever located beneath the fly wheel and having a shoe on one end adapted to be forced upwardly to engage said fly wheel to stop the movement of the gears, and a spring for automatically

drawing said shoe out of engagement with 10 said fly-wheel substantially as described.

Signed at New York city, in the county of New York, and State of New York, this seventh day of August A. D. 1906.

LOUIS A. HARTMANN.
